MAT FOR TENTS

Edward D. Barker, New Carlisle, Ohio

Application February 8, 1951, Serial No. 210,043

4 Claims. (Cl. 135—1)

(Granted under Title 35, U. S. Code (1952),
sec. 266)

1

The invention described herein, if patented, may be manufactured and used by or for the Government for governmental purposes, without the payment to me of any royalty thereon.

This invention relates to tents generally and has for its primary object to provide a floor of flexible material which is maintained taut at all times and provides a substantial border around the periphery of the tent.

Another object of the invention consists in the provision of a flexible floor for tents which is provided with apertures for receiving the lower ends of the tent poles, and means for preventing the passage of cold air, drafts, etc., up through such apertures.

A still further object of the invention resides in the provision of such a floor in which the pole-receiving openings are encompassed by depending flexible sleeves or pockets and tying cords or tapes for securing the walls of the sleeves or pockets into sealing engagement with the tent poles.

Other objects and advantages of the invention will be apparent from the following description when taken in connection with the accompanying drawings, in which

Figure 1 is a side elevational view of a tent mounted upon the novel floor construction;

Figure 2 is a plan view of the flooring per se;

Figure 3 is an enlarged detail plan view of a section of the flooring around one of the pole-receiving openings and showing the manner of attaching the sleeves about the openings;

Figure 4 is an enlarged vertical sectional view through a portion of the flooring including the pole-receiving opening and sleeve, and showing one of the poles in dotted outline; and

Figure 5 is a horizontal sectional view taken through one of the sleeves.

Referring to the drawings in more detail, the numeral 1 indicates a tent of any preferred construction provided with the usual guy lines 2 and 3, the latter having their upper ends secured to a reinforced portion 4 of the tent wall.

The flooring for the tent is indicated generally by the numeral 5 and may consist of a rectangular strip of canvas or other suitable flexible material suitably treated on its ground-engaging face. The area of the flooring is somewhat in excess of the area of the tent with which it is to be associated and is reinforced at its edges by a turned-over portion 6 suitably secured to the body of the fabric by lines of stitching. Secured along the reinforced edges 6 of the flooring is a plurality of loops 7 adapted to receive pegs 8 so as to anchor the flooring to the surface on which the tent is to be mounted and to maintain the flooring taut.

2

In the present illustration the tent is provided with four poles 9 and the flooring is provided with four symmetrically arranged apertures through which the lower ends of the poles are passed when the tent is installed upon the flooring. An important feature of the present invention resides in the provision of means for excluding cold air, drafts, etc., from passage up around the poles 9 up into the tent, and for this purpose, as well as for the purpose of preventing the flooring from "riding up" the poles, each aperture 10 is provided with a depending sleeve 11 preferably formed of leather.

Surrounding each aperture 10 is a reinforcing patch 12 suitably stitched to the flooring and serving to reinforce that portion of the flooring 5 to which the sleeve 11 is attached. As indicated in Figure 3, the upper end of each sleeve or guard 11 is provided with radially extending tabs 13 which are bent down onto the flooring around the aperture 10 and stitched in position by double rows of stitching 14, as clearly indicated in Figure 4.

Each sleeve 11 is preferably formed of a strip of leather doubled over and flanged as indicated by the numeral 15, and intermediate its ends the sleeve is provided with a tying tape 16. The mid-portion of the tape may be folded over the flanges 15 and the several parts stitched together by lines of stitching 17. The free ends of the tape thus provided are adapted to be drawn around the sleeve 11 after the particular pole line has been inserted therethrough and drawn together and tied, as indicated in Figure 1, so as to collapse the sleeve about the pole for the purpose of excluding the entrance of cold air, drafts, etc., to the interior of the tent.

From the foregoing description it will be noted that I have provided a flexible-type flooring for tents which is securely held in extended position, not only by the tent pegs 8 but also by the poles 9 which extend downwardly through the openings 10; that the flooring as shown herein provides a marginal portion extending about the tent, and that the possibility of cold air passing through the apertures 10 of the flooring is reduced to a minimum by reason of the depending sleeves or guards 11 encircling the lower ends of the tent poles and collapsed and secured about the same by means of the tying tapes 16.

I claim:

1. A flexible floor for tents including a strip of fabric provided with pole-receiving apertures, means for preventing the passage of currents of air up through said apertures, said means includ-

ing a flexible sleeve or pocket encircling each aperture and depending therefrom.

2. A flexible floor for tents including a strip of fabric provided with pole-receiving apertures, means for preventing the passage of currents of air up through said apertures, said means including a flexible sleeve or pocket encircling each aperture and depending therefrom, and means attached to each sleeve for collapsing the sleeve about a tent pole positioned therein.

3. A flexible floor for tents including a strip of fabric, a plurality of loops secured to the edges of the fabric for receiving anchoring pegs, said fabric provided with pole-receiving apertures spaced inwardly of its edges, a flexible sleeve encircling each aperture and depending therefrom, and a binding tape attached to the exterior of each sleeve for collapsing the sleeve about a tent pole positioned therein.

4. A flexible floor for tents including a strip of fabric, said fabric provided with pole-receiving apertures, a flexible sleeve encircling each aperture, and a binding tape attached to the exterior of each sleeve for collapsing and securing the sleeve about a tent pole positioned therein.

EDWARD D. BARKER.
